UNITED STATES PATENT OFFICE.

HERMANN SCHRODER, OF NEW YORK, N. Y.

RESONANCE-CHAMBER FOR SOUND-REPRODUCING APPARATUS.

1,395,602.

Specification of Letters Patent.

Patented Nov. 1, 1921.

Application filed June 4, 1920. Serial No. 386,466.

To all whom it may concern:

Be it known that I, HERMANN SCHRODER, a citizen of the United States, residing at New York, in the county of New York and State of New York, have invented certain new and useful Improvements in Resonance-Chambers for Sound-Reproducing Apparatus, of which the following is a specification.

10 This invention relates to improvements in sound reproduction apparatus and more particularly to an improved resonance box, sound chamber and sound outlet for all types of box, cabinet, and table phonographs.

15 One of the primary objects of the present invention is to provide a resonance chamber possessing features which will adapt it to modulate and at the same time improve the quality of the tones reproduced and thus 20 obviate all harsh and discordant sounds and greatly increase the faithfulness with which the sounds are reproduced.

25 Another object of the invention is to provide for an increase in the carrying quality of the reproduced sounds.

30 A further object of the invention is to provide a resonance box, sound chamber or basin so constructed as to adapt it to contain a volume of water or other liquid in order to produce the advantageous results above mentioned.

35 The invention also has as its object to provide a resonance chamber and sound outlet which will add greatly to the appearance of the instrument in connection with which it is employed.

In the accompanying drawings:

Figure 1 is a perspective view of a cabinet phonograph equipped with the resonance chamber and sound outlet embodying the invention;

Fig. 2 is a horizontal sectional view through the forward portion of the cabinet and illustrating the forward portion of the 45 said chamber in plan;

Fig. 3 is a view partly in side elevation and partly in front to rear section illustrating the manner in which the resonance chamber is arranged within the cabinet of the phonograph, and also clearly showing method of draining the said chamber of its 50 contents;

Fig. 4 is a perspective view of the resonance box removed from the cabinet.

55 In the drawings the numeral 1 indicates in general the cabinet of a phonograph, 2

the tone arm, and 3 the compartment within the upper portion of the cabinet in which is ordinarily housed the usual wooden resonance box. For the purposes of the present 60 invention, the cabinet 1 is open at the upper portion of its front as indicated by the numeral 4, or, in other words, the compartment 3 opens through the front of the cabinet.

65 The resonance chamber embodying the present invention is clearly shown in Fig. 4 of the drawings and the said chamber is indicated in general by the numeral 5 and comprises a flared body 6 having side walls 7, a 70 top wall 8, and a bottom wall 9. The chamber 5 is of general rectangular form in cross section but its side walls 7 converge in a rearward direction and its top wall 8 is inclined downwardly and rearwardly so that 75 the chamber is of greater dimensions at its delivery end 10 than at its inner end. The said walls of the chamber at the inner end thereof merge and form an upwardly curved neck 11 tapered in the direction of its upper 80 end and connected in any suitable manner at its said end with the lower end of the tone arm 2. The delivery end 10 of the resonance chamber is disposed approximately flush with the open side 4 of the cabinet 1 as clearly shown in Fig. 1 of the drawings, or it may protrude in an ornamental manner upwardly or downwardly away from the said front and while the said end of the resonance box is illustrated in the 90 drawings as left entirely open, it will be understood that any of the ordinary means may be employed for screening, closing, or partly closing the same.

95 As previously stated, the resonance box of the present invention is so constructed that it may contain a volume of water or other liquid which will serve as a medium for modulating the reproduced tones and at the same time improving their quality. 100 In order that the resonance chamber or sound outlet may be so adapted, its bottom wall 9 is disposed horizontally and the said wall is extended forwardly beyond the delivery end 10 of the box to form the bottom 105 12 of a basin indicated in general by the numeral 13. Likewise the bottom wall 12 is extended laterally as at 14 and at its lateral portions is likewise preferably extended rearwardly as at 15 so that the bottom of 110 the basin will not only extend in front of the cabinet 1 but also partly at the sides

thereof. The purpose of this construction will presently be made clear. The numeral 16 indicates the upright wall of the basin which wall has a front portion 17, side portions 18 which extend at the outer edges of the respective portions 16 of the bottom of the basin, and other portions 19 which extend opposite the portions 18 and around the forward corners of the open front of the compartment 3 as at 20 and are joined to the side walls 7 of the resonance chamber. Thus the basin extends not only within the interior of the compartment 3 but also across the front of the said compartment 15 and consequently across the front of the cabinet, and also partly at the sides of the cabinet.

The resonance chamber will preferably be made of glass although any other material or combination of materials may be employed for this purpose and it will be understood that the exposed portions of the said chamber may be suitably ornamented so as to add to the attractive appearance of 25 the cabinet of the instrument as a whole. In the lateral portions of the basin, and if desired even in the front portion thereof, flowers may be arranged so as to further add to the appearance of the instrument, the basin 30 being filled to any desired level with water or any other liquid as best shown in Figs. 1 and 3 of the drawings.

In order that the liquid may be drawn off whenever desired, a drain pipe 20 is fitted 35 through the rear end of the basin as best shown in Fig. 3 of the drawings and leads through the rear wall of the cabinet 1 and is provided with any suitable type of faucet 21.

40 As before stated, cut flowers or aquatic plants may be arranged within the lateral or even the front portion of the basin, and also if desired various aquarium ornaments may be arranged within the basin.

45 While as stated it is preferable that the

resonance chamber be made of glass, any material may be employed for this purpose so long as it is of a resonant nature and otherwise suitable for the purpose. By reason of the presence of the volume of water within 50 the basin of the resonance chamber, the tones as reproduced are modulated in the same manner as are other musical sounds when heard across a body of water.

Having thus described the invention, what 55 is claimed as new is:

1. A resonance chamber for sound reproducing apparatus having in its lower portion a bottom, and a wall completely surrounding the bottom and providing a basin 60 adapted to contain a volume of liquid.

2. A resonance chamber for sound reproducing apparatus having a liquid containing basin forming its lower portion, the said basin extending to a point in advance of the 65 delivery end of the chamber.

3. A resonance chamber for sound reproducing apparatus having a liquid containing basin forming its lower portion, the said basin extending to a point in advance of the 70 delivery end of the chamber and being also extended laterally.

4. A resonance chamber for sound reproducing apparatus having bottom, side and top walls, the bottom wall being extended 75 beyond the delivery end of the chamber, and an upright wall surrounding the extended portion of the bottom wall whereby to provide a liquid containing basin.

5. A resonance chamber for sound reproducing apparatus having a lower portion 80 constructed to contain a volume of liquid, and valved means whereby the liquid may be drained from the said chamber.

In testimony whereof I affix my signature. 85

HERMANN SCHRODER.
